UNITED STATES PATENT OFFICE.

OSKAR LÖTZSCH, OF DRESDEN, GERMANY.

SHUTTLE-CHANGING MECHANISM FOR LOOMS.

1,109,297.

Specification of Letters Patent.

Patented Sept. 1, 1914.

Application filed August 16, 1912. Serial No. 715,435.

To all whom it may concern:

Be it known that I, OSKAR LÖTZSCH, a subject of the German Emperor, residing at Dresden, Saxony, Germany, have invented 5 a certain new and useful Improved Shuttle-Changing Mechanism for Looms, of which the following is a specification.

This invention relates to a device for the automatic exchange of shuttles in weaving 10 looms.

In the accompanying drawings:—Figure 1 is a side elevation, Fig. 2 a front elevation, and Fig. 3 a plan of an embodiment of the invention.

15 As soon as the material in the shuttle has been exhausted to such an extent that a new shuttle with a full spool or pirln is to be introduced, the lever *a* is raised (dotted position) slightly upward by any desired de-

20 vice, such as a shaft similar to that described for instance, in the U. S. Patent to Wyman No. 642,946. During the return of the lay or batten, the lever *a* strikes the double lever *b* which is pivoted to the batten. Conse-

25 quently the other end, which engages a recess *d* of the slide *c* is pushed out and the slide is set free, and the said slide will be pulled upward by the spring *e* and in that way the inner part of the shuttle box bot-

30 tom *f* driven upward, and the empty shuttle, instead of being driven into the shuttle box, will now be driven under the raised portion of the shuttle box bottom *f* and out of the batten, the said shuttle falling into

35 a box (not shown) arranged at the side. The batten has at that time reached its rear-most position. As soon as the slide *c* begins to rise, the spindle *g* which is supported below the batten in two bearings *h*, is

40 rotated, as the spindle *g* is provided with a cam *i* which rests on a roller *k* provided on the slide *c*. As soon as the spindle *g* is turned, the stop arm *m* secured to the spindle *g*, is turned downward, in order to form

45 during the return a stop for the cam *o* rotatably mounted in a resilient manner on the oscillating hooked tension lever *n*. In that way, the returning hooked tension lever *n* connected by lever arms to the eccentric

50 *p* and controlled by the spring *q*, is depressed by the cam *o* and coupled by the hook *r* and the bolt *s* to the shuttle feeder *t* and pulled toward the batten.

The feeder *t* is mounted laterally on the 55 loom and is guided in an overhanging portion arranged on the wall of the loom, to

which overhanging portion is secured the shuttle magazine *u*. As soon as the feeder *t* is connected to the eccentric *p* by the lever arms and driven, the lever *w* resting on the same and controlled by the spring *v*, will be lowered together with the tongue *y* with closing hook *z*, mounted on the same spindle *x*, and the closing flap *A* which was hitherto locked, is released. The feeder *t* pulled 60 toward the batten, takes one shuttle from the magazine *u* and forces upward the flap *A* which closes the magazine at the bottom and is pivoted at both sides, and engages under the cam *C* arranged on the front 65 shuttle box wall *B*, whereby the wall *B* of the shuttle box is forced to rise with the flap *A*, in order to enable the shuttle to slide 70 freely into the shuttle box. The feeder *t* has then introduced a new shuttle. At the same time the part *f* of the shuttle box bottom 75 is brought into its former position owing to the sliding bracket *D* secured to the feeder *t*, striking the lever *l* and forcing the latter back, whereby the spindle *g* and 80 the cam *i* are turned downward, and the stop arm *m* upward, the slide *c* being pulled downward by the cam *i* by means of the roller *k*, and the double arm *b* can engage then with the groove *d*, in order that the 85 slide may be held down by the arm *b*. During the return of the hooked tension lever *n* by the eccentric, the spring controlled feeder *t*, released by the hooked lever *n*, returns to its position of rest. 90

What I claim as my invention and desire to secure by Letters Patent is:—

1. In a shuttle changing mechanism for looms, a shuttle magazine, a batten, a double armed lever pivoted on the batten, a lever adapted to strike the double armed lever, a slide which is set free by said double armed lever, an inner part of the shuttle box bottom which is driven upward by said slide, a spindle provided with an arm resting on a roller provided on said slide, a stop arm secured to said spindle, a cam which is engaged by the stop arm when the batten moves forward, a hooked lever on which the cam is pivotally mounted, an eccentric for oscillating said lever, a feeder pulled toward the batten by the hooked lever, a lever operating a closing flap for the shuttle magazine and resting on the feeder, a shuttle box, means whereby the shuttle box is forced to open when the flap for the shuttle magazine rises and means whereby 100

105

110

the parts are returned to normal position, for the purpose set forth.

2. In a shuttle changing mechanism for looms, a shuttle magazine, a batten, a double armed lever pivoted to the batten, a lever adapted to strike the double armed lever, a slide mounted in the batten which is set free by said double armed lever, an inner part of the shuttle box bottom which is driven upward by said slide, a spindle, a pair of bearings supporting said spindle, an arm on said spindle, a roller provided on said slide, said arm resting on said roller, a stop arm secured to said spindle, a cam 10 which is engaged by the stop arm when the batten moves forward, a hooked lever positioned by said cam, an eccentric for oscillating said lever, a shuttle feeder engaged

by said hooked lever and pulled toward the batten, a double arm lever positioned by contact with said shuttle feeder, a closing flap for the shuttle magazine, a hook locking the closing flap and coupled to the double armed lever, a shuttle box, a movable front wall to the shuttle box and arms arranged thereon whereby said wall is forced to rise with the closing flap, and means for returning the parts to their normal position, for the purpose set forth.

In testimony whereof I have signed my name to this specification in the presence of two subscribing witnesses.

OSKAR LÖTZSCH.
